UNITED STATES PATENT OFFICE.

SAMUEL W. REYNOLDS, OF SCRANTON, PENNSYLVANIA.

HAND-OPERATED PROPELLING MECHANISM.

1,126,569.

Specification of Letters Patent. Patented Jan. 26, 1915.

Application filed April 30, 1912. Serial No. 694,228.

To all whom it may concern:

Be it known that I, SAMUEL W. REYNOLDS, a citizen of the United States, residing at Scranton, in the county of Lackawanna and 5 State of Pennsylvania, have invented a new and useful Improvement in Hand-Operated Propelling Mechanism for Boats, of which the following is a specification.

The primary object of this invention is 10 to provide a simple and effective mechanism for propelling boats by hand while the operator is (or operators are) seated either facing the bow or stern and which will utilize as much of the force imparted by the 15 operator (or operators) as possible in propelling a boat either forward or backward.

In the accompanying drawings forming 20 part of this specification, Figure 1 is a side elevation of a boat partly broken away to expose the interior operating mechanism; Fig. 2 is a plan of a detail portion of the boat looking at the operating mechanism; Fig. 3 is a side elevation partly in section of the 25 ratchet mechanism employed for propelling the drive shaft; Fig. 4 is a longitudinal section of part of the ratchet mechanism, and Fig. 5 is a cross section taken upon the line X—X of Fig. 4.

20 In the drawings A represents a boat having a propeller 2 of ordinary construction mounted upon a main shaft 3. Said propeller shaft carries a fly wheel 4 and is journaled in suitable bearings 5 and 6 which are 25 secured to the hull of the boat. The bearings 5 and 6 have also journaled therein a drive shaft 7 lying parallel with the propeller shaft and carrying right and left hand threads between the journals 5 and 6. 30 This drive shaft is connected at one end to the propeller shaft by gears 8 and 9 which intermesh and are so proportioned in size as to increase the speed imparted by the drive shaft to the propeller shaft. The drive 35 shaft is driven by means of a clutch 10 which is reciprocated longitudinally thereon by means of a rocker arm 11, said rocker arm being secured to the yoke frame 12 of the clutch by means of a connecting rod 13. 40 The rocker arm is journaled at its lower end in the support 14 which is secured to the hull of the boat and its upper end is provided with a handle 15 by means of which the arm 11 can be swung backward and forward in the boat while the operator is (or

operators are) seated either facing the bow or the stern as desired.

The connecting rod 13 is pivotally connected between the ends of the rocker arm and to the yoke frame 12 of the clutch between a pair of flanges 16 thereon. The yoke frame is slidably mounted upon the propeller shaft 3 so as to prevent the clutch from turning as it is reciprocated on the shaft 7. The clutch proper consists of a 60 pair of collars 17 and 18, the one being fitted internally to the right hand threads of the propeller shaft 7 and the other to the left hand threads of said shaft. Each of these collars has its periphery toothed longitudinally to form longitudinal grooves 19 in which dogs 20 and 21 are adapted to play and engage, said dogs being held in the body 22 and lying idle in the channel 23 therein. Each of these dogs is formed with a shoulder 24 for engaging the teeth at the sides of the grooves 19, one end of each dog being also formed with end shoulders 25 lying in notches 26 in the body 22 to limit longitudinal motion of the dogs but permitting the 70 dogs to be tilted out of engagement with the teeth on the collars, the lower surface below the notches 26 in the body 22 being inclined at 27 to permit said tilting action of the dogs. 85

On the outside of the body is a sleeve or housing 28 secured by means of a bolt 29 to said body and lying within this sleeve is a guide plate 30 carrying on its lower surface a leaf spring 31, the ends of which slide upon the surface of the dogs, said guide and spring being free to move longitudinally in the channel 23 over the dogs. Either dog 20 or 21 when in engaging position with the clutch is held into engagement with the 90 same by one end of the spring 31. The upper portion of the guide 30 has a lug 32 which is free to move endwise in the longitudinal slot 33 in the sleeve 28. When the guide 30 is moved in one direction by the projecting lug 32 one end of the spring 31 is adapted to tilt one of the dogs out of engagement with the teeth with which it cooperates on the collars 17 and 18 and when reversed the other end of the spring 31 tilts the other dog out of engagement with its coöperating collar, thereby causing motion to be communicated by the clutch to the drive shaft and revolving the latter in forward or backward direction according to 105 110

which dog is engaged in the clutch. When the spring is in median position both of the dogs are held engaged with the two collars 17 and 18, the drive shaft within being locked and prevented from revolving in either direction.

The shoulders 24 on the dogs 20 and 21 are positioned on opposite sides of the axis of the drive shaft 7 and the collars 17 and 18, so that one side of the shoulders 24 lies adjacent the side of the channel 23 while the other side engages with one of the teeth formed on the collars 17 and 18. The width of the shoulders 24 is greater than the width of the grooves 19, so that when the collar which is being engaged tends to turn in a reverse direction to the rotation of the drive shaft as in the return stroke of the clutch, the teeth on the collar will force the shoulder 24 up out of engagement with the same to allow the collar to rotate in a reverse direction and prevent the reversing of the shaft 7.

For the purpose of operating the clutch dogs, a shift rod 34 is slidably mounted upon the side of the connecting rod 13, said rod being loosely connected to the lug 32 on the slide 30 through a slot 33 in the yoke by a bell crank lever 35 which is journaled at 36 between its ends on the side of the yoke.

In operation the rocker arm 11 is oscillated by means of the handle 15, the clutch being reciprocated during said oscillation and the drive shaft 7 revolved in the direction according to whichever dog is engaged in the clutch. To reverse the motion of the propeller the shift rod 34 is reversed in position and when it is desired to lock the clutch so as to prevent the rotation of the propeller,

the shift rod 34 is shifted into median position.

In accordance with the patent statutes I have described the principles of operation of my invention together with the apparatus which I now consider to represent the best embodiment thereof but I desire to have it understood that the construction shown is only illustrative and that the invention can be carried out by other means and applied to uses other than those above set forth within the scope of the following claim.

Having described my invention, what I claim as new and desire to protect by Letters Patent is:—

Propelling mechanism for a boat, comprising, in combination, a propeller, a shaft in said boat upon the end of which said propeller is mounted, a drive shaft lying parallel to and connected with said propeller shaft to revolve the latter, a clutch yoke 60 slidably mounted upon said propeller shaft and through which said drive shaft passes, a clutch in said yoke and threaded into engagement with said drive shaft to revolve the latter in forward or backward direction, means for reciprocating said yoke member longitudinally on said drive shaft and means carried by said reciprocating means for reversing said clutch and causing the drive shaft to revolve in reverse direction.

In testimony whereof, I have signed my name to this specification, in the presence of two subscribing witnesses.

SAMUEL W. REYNOLDS.
